ETIENNE TESTE, OF PARIS, FRANCE.

AUTOMATIC MULTIPLE-NOTE HORN.

1,103,705.

Specification of Letters Patent.

Patented July 14, 1914.

Application filed April 3, 1911. Serial No. 618,551.

To all whom it may concern:

Be it known that I, ETIENNE TESTE, of 18 Rue des Bois, in the city of Paris, Republic of France, machine maker, have invented 5 Improvements in Automatic Multiple-Note Horns, of which the following is a full, clear, and exact description.

This invention relates to improvements in the horn which forms the subject of former 10 Patent No. 970136 of 13th September 1910.

These improvements are essentially characterized by: 1. An air distributor provided with several series of openings capable of being brought opposite the trumpets and so 15 arranged that the sounds successively emitted will produce a complete musical phrase or a number of musical phrases. 2. The operation of the air distributor by a spring-pressed pawl jointed to a metal collar adapted to rotate on the distributor when the bulb is compressed and to act on a ratchet-wheel keyed to the distributor at the time that the air enters the bulb. 3. Means for arresting the air distributor. 4. A construction which permits of either entirely 20 stopping the emission of sound or of producing a uniform sound.

The invention will be described with reference to the accompanying drawings 30 wherein—

Figure 1 shows a perspective view of the apparatus; Figs. 2 and 3 a front view and side view respectively of the portions constituting the air distributor, drawn to a 35 larger scale; Fig. 4 a vertical section on line A—A of Fig. 3 and Fig. 5 a similar view showing the displacement of the collar which carries the pawl. Fig. 6 shows the air distributor separately. Fig. 7 is a vertical longitudinal section of the distributor. Fig. 8 shows separately the means for enabling the emission of sounds to be suspended. Fig. 9 is a vertical section on line B—B of Fig. 3.

As stated in the specification of the former patent the horn comprises a metal cylinder *a* to which are fixed the trumpets *b*, *b*¹, *b*², *b*³ which communicate with the cylinder through the openings *c* of rectangular form 50 made in the periphery of the latter and situated at different positions in the length of the cylinder, as indicated in Fig. 4. Within the cylinder *a* the distributor, which permits of directing the air expelled by the bulb *d* successively into one of the trumpets *b*, *b*¹, 55 *b*² or *b*³, is fitted, said distributor being con-

stituted by a metal tube *e* closed at one extremity by a disk *e*¹ and at its other extremity by a ratchet-wheel *f* whose function will be explained later on. The periphery of the tube *e* is provided with rows of openings *g*, *g*¹, *g*², *g*³, *g*⁴, five rows being shown in the drawings. The openings *g*, which are of rectangular form and placed close to one another, are arranged in such manner as to 60 come in front of the tube *h* which puts the cylinder *e* into communication with the air bulb *d*. The rows of openings *g*¹, *g*², *g*³, *g*⁴ are arranged at either side of the row of 65 openings *g* so as to put the cylinder *e* into communication with the trumpets *b*, *b*¹, *b*², *b*³. The number of openings for each of the series *g*¹, *g*², *g*³, *g*⁴ may be varied and depends upon the grouping of the notes of the musical phrases which are to be produced. 75

The tube *e* is provided with an inner concentric tube *e*² of smaller diameter, one of whose extremities is attached to the disk *e*¹ while the other extremity is bell-mouthed and abuts against the interior surface of the 80 wall of the tube *e* (Fig. 7) so as to leave an annular space *e*³ between the two into which the air entering through the openings *g* passes before passing through the openings *g*¹, *g*², *g*³, or *g*⁴. The tube *e*² thus lessens the 85 capacity of the tube *e* and allows the air to act upon the reeds of the trumpets when it arrives in the annular space *e*³.

The tube *e* is held in the cylinder *a* by a screw *e*⁴ bearing upon the end of a cover *a*¹ 90 which closes one end of the cylinder *a* and screwing into a socket *e*⁵ formed on the disk *e*¹. In the space between the disk *e*¹ and the cover *a*¹ a flat metal spring *i* is arranged, the one end of said spring being fixed to 95 the cover while its other bears against the disk *e*¹, the spring thus constituting a brake to limit the rotation of the distributor and prevent it from rotating a distance greater than that separating the teeth of the ratchet-wheel *f*. The ratchet-wheel is contained in a box *a*² whose diameter is greater than that of the cylinder *a* with which it is integral, said box *a*² being closed by a cover *a*³ held in place by a bayonet fastening. The tube *h*, debouching opposite the openings *g* of the distributor and leading the air into the latter, is arranged on a transverse cylinder *j* which itself communicates at one of its extremities with another cylinder *k* placed parallel with the tube *h*. Upon one of the extremities of the cylinder *k* an air-bulb *d* is 100 105 110 115

secured in any convenient manner. The cylinder *j* contains an arrangement which permits the horn to emit tremolo sounds, but which, having formed the subject of another 5 patent, need not be here described.

Within the cylinder *k*, which, as just stated communicates with the cylinder *j*, there is fitted a hollow piston *l* to one of whose extremities a rod *m* (adapted to operate 10 the air distributor as will be seen hereafter) is jointed. The one end of the piston *l* is provided with ports *m*¹ surrounding the rod *m*, while its other end is furnished with a valve *n* which permits the escape into the 15 bulb *d* of the air entering the piston through the openings *m*¹ (Fig. 4). The piston *l* is constantly pressed toward the bulb *d* by a spiral spring *o* bearing against the ring cover *p* attached to the end of the tube *k* 20 and at the other end against the upper end of the piston. The rod *m* is jointed on the one hand to the piston *l* and, on the other hand to a lug *q* in one with the collar *q*¹ which surrounds the air distributor immediately behind the ratchet-wheel *f*. 25 This collar *q*¹ passes into the box *a*² by an opening *a*⁴. To the collar *q*¹ there is hinged a pawl *q*² which constantly tends to engage with the teeth of the ratchet wheel *f* under 30 the stress of a spring *q*³.

The operation is as follows: When pressure is exerted upon the bulb *d* the piston *l* is moved forward by the air and the movement of the rod *m* partially rotates the collar *q*¹ which carries with it the pawl *q*² which becoming released from the tooth of the ratchet wheel with which it was engaged, slides over the periphery of the ratchet-wheel and comes into engagement with the next tooth. 35 When the bulb *d* is released, after the air has been expelled from it, the piston *l* returns to its former position under the action of the spring *o*, drawing with it the rod *m* which in its turn draws with it the collar *q*¹ and the pawl. The pawl, being 40 then in engagement with the ratchet-wheel *f*, it turns the latter to an extent corresponding to one tooth of the ratchet-wheel. Thereupon a fresh opening *g*¹, *g*², *g*³ or *g*⁴ comes 45 opposite the trumpets *b*, *b*¹, *b*² or *b*³, so that when the bulb *d* is again acted on, the air passing into the distributor escapes by this 50 opening and so on, the distributor being partially rotated by the spring *o* acting upon 55 the piston *l*. This arrangement thus insures the proper working of the air distributor.

It is to be furthermore noted that the distributor being contained in the box *a*² which is closed by the cover *a*³, is sheltered from 60 dust and rain.

To fix the collar *q*¹ in a predetermined position I fix to the box *a*² a small cylinder *r* through which extends a pin *r*¹ carrying a milled button *r*² on one of its extremities, 65 the other extremity of the pin being adapted

to engage either in a slot *r*³ or in a cut-away portion *r*⁴ of an extension of the collar *q*¹ as shown in Fig. 5 of the drawing. The pin *r*¹ is fixed in the desired position, that is to say, in the engaged position or not, by means of a spring-pressed bolt *s* the extremity of which engages in a groove in the pin. 70

If it is desired that the distributor shall turn normally, the pin *r*¹ is retracted so that its extremity is out of contact with the extension of the collar *q*¹. If it is desired to obtain a uniform sound, pressure is exerted on the pin *r*¹ so as to cause its extremity to engage in the slot *r*³. Lastly, if it is desired to entirely stop all emission of sound the pin *r*¹ is engaged in the cut-away part *r*⁴ in which case the piston *l* closes the opening by which the cylinder *k* communicates with the cylinder *j* while the pin *r*¹ locks the piston so that no air can pass into 85 the distributor.

The operation of the horn thus constructed is the same as that described in the specification of the former patent, that is to say, the air expelled by the bulb *d* passes (after 90 having entered the cylinder *k* and actuated the trembler) by way of the tube *h* into the air distributor *e*, thence escaping through one of the trumpets *b*, *b*¹, *b*², *b*³ as has been stated above. 95

In order to facilitate the introduction and withdrawal of the cylinder *e* it is furnished with a button *e*⁶ attached centrally to the ratchet-wheel *f*. The screw *e*⁴ at the other extremity of the cylinder *e* enables the latter to be turned from the exterior in order to bring opposite the ratchet *q*² the tooth of the ratchet-wheel *f* arranged in line with the opening *g* to produce the first note of the musical phrase, the point being indicated by a sign traced on the ratchet-wheel. As the air distributor *e* can be withdrawn with the greatest facility it may be readily replaced by another provided with openings arranged in a different order for the purpose 100 of producing other musical phrases. Thus it is possible with a single apparatus to obtain an indefinite number of different musical airs by merely changing the distributor *e*. This change may however be effected by 105 producing upon a cylinder of suitable length two or more series of openings each corresponding to a different musical phrase. 110

Claims:

1. An automatic multiple-note horn, comprising a plurality of trumpets, an air distributor provided with a series of openings capable of coming successively in front of the trumpets and arranged in such manner that the sounds successively emitted produce one or several predetermined musical phrases, said air distributor being tubular and furnished with an internal concentric sleeve which forms between it and the internal periphery of the distributor an annu- 120
- 125
- 130

lar chamber which directs the air directly into the reeds of the trumpets.

2. In an automatic multiple note horn, an air distributer provided with a ratchet wheel, a collar movable on the distributer, a pawl carried by the collar and engaging the ratchet wheel, a piston having connection with the collar, an air bulb for forcing air against the piston and moving the latter in a direction adapted to slide the pawl along the ratchet wheel, and a spring for

moving the parts in the opposite direction and actuating the distributer.

The foregoing specification of my improvements in automatic multiple-note horns signed by me this tenth day of March, 1911.
